US00D990885S

(12) United States Design Patent (10) Patent No.: US D990,885 S
(45) Date of Patent: * Jul. 4, 2023

(54) FOLDING STORAGE BOX

(71) Applicant: Guangzhou Yaweiqi Trading Co., Ltd., Guangzhou (CN)
(72) Inventor: Yonghong Xiang, Guangzhou (CN)
() Term: 15 Years
(21) Appl. No.: 29/831,748
(22) Filed: Mar. 23, 2022
(51) LOC (14) Cl. 03-01
(52) U.S. Cl. USPC D3/299; D12/423
(58) Field of Classification Search

(57) CLAIM

The ornamental design for a folding storage box, as shown and described.

DESCRIPTION

FIG. 1 is a first perspective view of a folding storage box showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of the folding storage box shown in another alternate configuration in a folded, open state; and,

FIG. 10 is another perspective view thereof.

1 Claim, 10 Drawing Sheets
